STYLUS ARM FOR RECORDERS

Howard N. Fawcett, Briarcliff Manor, N.Y., assignor to Cambridge Instrument Company, Inc., Ossining, N.Y.

Filed Mar. 16, 1971, Ser. No. 125,011

Term of patent 14 years

Int. Cl. D14—01

U.S. Cl. D26—14 B

FIG. 1 is a side elevational view of the stylus arm for recorders in accordance with the invention.

FIG. 2 is a top view of the design shown in FIG. 1.

FIG. 3 is a cross-sectional view of FIG. 1 taken along the line 3—3 thereof.

FIG. 4 is a left-hand end view of the design shown in FIG. 2.

FIG. 5 is a cross-sectional view of FIG. 2 taken along the line 5—5 thereof.

I claim:

The ornamental design for a stylus arm for recorders, as shown.
